UNITED STATES PATENT OFFICE.

CHARLES JESDALE, OF CHICAGO, ILLINOIS.

FUEL-MIXTURE HOMOGENIZER.

Application filed March 11, 1922. Serial No. 542,891.

This invention relates to attachments or accessories for gas engines and its purpose is to vaporize, mix and homogenize a liquid fuel mixture in its travel between the carbureter and the engine cylinders.

For the purpose of facilitating an understanding of my invention I have illustrated on the accompanying drawings one preferred embodiment thereof from an inspection of which, when considered in connection with the following description, the invention and many of its attendant advantages should be readily understood and appreciated.

Referring to the drawings:

Fig. 1 is a side view of a gas engine equipped with my invention;

Fig. 2 is a sectional view on the line 2—2 of Fig. 3;

Fig. 3 is a vertical sectional view on the line 3—3 of Fig. 2; and

Fig. 4 is an enlarged sectional view of the gasoline tank cap.

On the drawings, reference character 5 indicates generally a gas engine of any preferred construction equipped as is customary with the exhaust manifold 6 discharging into the exhaust pipe 7 and with the intake manifold 8 which receives its supply of fuel mixture from a carbureter 9 of any preferred construction. The liquid fuel is delivered to the carbureter from the fuel tank 11 through the supply pipe 12 in the usual manner.

My invention comprises a homogenizer adapted to be interposed in the fuel mixture passage between the carbureter and the engine cylinders, and while it may be disposed in any convenient location in this passage, it is illustrated herein as interposed between the upper end of the carbureter and the lower end of the manifold 8. The homogenizer comprises an outer shell 13 and an inner shell 14 preferably cast integrally therewith and for convenience in manufacture the device is made in two parts which are substantial duplicates of each other and are joined together along a central medial line by means of bolts 15 passed through apertures 16 in the opposed flanges 17 and 18 of the two sections. The shell is provided at its top with a flange 19 adapted to be connected to the manifold by bolts 21 and at its bottom with a flange 22 adapted to be connected with the carbureter by bolts 23.

The inner and outer shells 13 and 14 of the device are spaced apart to provide an in-

tervening surrounding passage 24 through which the fuel mixture is drawn from the carbureter into the manifold. The two shells, as previously stated, are preferably cast integral and united by webs or ribs 25 separated by elongated openings 26 through which the mixture flows. The walls of the passage 24 are serrated as shown providing a tortuous passage so that the mixture flowing therethrough is repeatedly deflected and mechanically broken up during its passage therethrough.

The chamber 27 formed within the shell 14 is adapted to serve as a heating chamber for heating the surrounding mixture to facilitate its vaporization. Heat is applied to this chamber by exhaust gases from the engine which are conducted from the exhaust pipe 7 into this chamber through a conduit 28 provided at its intake end with a deflector or vane 29 which intercepts a portion of the exhaust from the motor and directs it into the heating chamber. The delivery end of the conduit 28 communicates with the interior of the chamber 27 through a nipple 31 which enters the chamber 27, as shown in Fig. 3. After giving up heat units the exhaust gases escape from the chamber through another nipple 32 into a delivery pipe 33 by which they are discharged beneath the car.

It will be apparent, therefore, that the shell of the chamber 27 is raised to a high temperature by the exhaust gases delivered thereto, and as the fuel mixture flows through the tortuous passage 24 around this hot chamber, the mixture is not only vaporized by the hot walls of the chamber 27, but it is also mechanically disintegrated and homogenized by the repeated deflections resulting from the serrated form of the opposed walls forming the passage.

It is well known that the more highly volatile portions of the liquid fuel employed tend to vaporize in the supply tank, and heretofore this vapor has passed off and been dissipated and lost. My invention contemplates the utilization of this volatile portion of the fuel by delivering the same into the fuel mixture passage so that it is commingled with the fuel mixture delivered by the carbureter, and is then conducted to the cylinders where its power is utilized.

With this end in view my invention contemplates a connection between the lower portion of the homogenizer and the upper portion of the fuel tank, and, as herein illus-

trated, a pipe or tube 34 is connected at one end by means of the nipple 35 with the fuel mixture passage just above the carbureter, and by means of another nipple 36 with a sleeve 37 which is threaded into the flange 38 customarily surrounding the supply opening for the tank. The nipple 36 is provided at its inner end with a small nozzle opening 39 through which communication is established with the interior of the tank. The upper end of the sleeve 37 is closed by the customary cap 41.

The suction of the engine exerted through the intake manifold draws the vapors in the top of the fuel tank through the opening 39 into the pipe 34 by which they are delivered into the fuel mixture passage just above the carbureter. These vapors together with the vapors and unvaporized fuel delivered from the carbureter pass through the openings 24 in the homogenizer and after being alternately thrown from one wall to the other of the fuel passage through the homogenizer are delivered into the intake manifold 8. During the passage of the mixture from the line 34 and from the carbureter through the passageway 24, they are evenly or uniformly distributed about the inner shell by reason of the generally spherical shape of the two shells and passageway 24. This action is an obvious function of the spherical shells and baffles 14 which are concentrically arranged one with the other and transverse to the general direction of fuel flow. It will, of course, be appreciated that other constructions may be devised to perform the same function.

It should be apparent from the foregoing that I have provided an apparatus which is adapted to break up, vaporize and homogenize the fuel mixture delivered by the carbureter, and furthermore it is adapted to increase the efficiency of the mixture by commingling therewith the fuel vapors which are withdrawn from the upper portion of the fuel supply tank. The details of construction of the apparatus may, of course, be varied within considerable limits without departing from the scope of the invention.

I claim:

1. A fuel mixture homogenizer, comprising, inner and outer spherical shells spaced apart to provide a fuel mixture passage, one of said shells having an inlet and an outlet port to said passage, one of said shells being constructed and arranged to be heated and a series of baffles on opposed walls of the mixture passage relatively arranged to direct a fuel stream generally diagonally between said opposed walls, said baffles being arranged transverse of the passages between said ports.

2. A fuel mixture homogenizer comprising, inner and outer concentric spherical shells spaced apart to provide a passage for fuel flow therethrough one of said shells having an inlet and an outlet port to said passage, and means on opposed walls of said passage and transverse to the passage between said ports constructed and arranged to receive and distribute the fuel stream between said walls.

3. In a fuel mixture homogenizer, outer and inner spherical shells, concentrically spaced one from the other to provide a fuel stream passageway therebetween, one of said shells having an inlet and an outlet port to said passage, said passageway being of substantially uniform cross-section on any diameter substantially transverse to the passageway between said ports, and staggered baffles in said passageway extending wholly around said passageway and transverse to the general direction of said passageway.

4. In a fuel mixture homogenizer, outer and inner spherical shells, concentrically spaced one from the other to provide a fuel stream passageway therebetween, said passageway being of substantially uniform cross-section on any diameter transverse or substantially transverse of the passageway, staggered baffles in said passageway extending wholly around said shells and transverse to the passageway, and means for supplying a heated medium to the interior of the inner shells.

CHARLES JESDALE.
